ATTORNEY

UNITED STATES PATENT OFFICE.

KATHARINE JULIA CLINTON CARVILLE, OF NEW YORK, N. Y.

PARCEL-DELIVERY SYSTEM.

SPECIFICATION forming part of Letters Patent No. 530,747, dated December 11, 1894.

Application filed February 19, 1894. Serial No. 500,759. (No model.)

To all whom it may concern:

Be it known that I, KATHARINE JULIA CLINTON CARVILLE, a citizen of the United States, residing in the city of New York, county and 5 State of New York, have invented new and useful Improvements in Parcel-Delivery Systems, of which the following is a specification.

My invention relates to improvements in package or parcel delivering systems, and the 10 same may be operated by pneumatic pressure or by any other source of power suitable for the purpose.

My invention relates particularly to a carrier and means to discharge the contents of 15 the carrier at the point of delivery and to return the carrier to its point of departure by the force of gravity.

I have illustrated my invention in the accompanying drawings, in which—

20 Figure 1 is a side view showing a pouch B which is intended to be on a wall or suitable support b' and b'. A is intended to represent a sectional view of the pneumatic pipes or other guides that may be employed leading 25 from a point of departure to a point of delivery, and return.

In Fig. 2 I have shown the view of the same looking at the pouch in the direction of the arrow x. In this figure the pipes which are 30 behind or within the support or wall b' are shown in dotted lines. B is a pouch preferably of wire-work secured to the wall and having an opening or door b⁴ pivoted at b⁵ and secured by the latch b⁶. The pipes or guides

35 A enter into this receiver through an aperture in the wall b' and b'. This aperture is preferably closed by the door or lid b² pivoted at b³, and adapted to be thrown open as will be hereinafter described. C is a gong suitably 40 secured to the wall b' and b'. c' is a plunger engaging the hammer c³ which is pivoted at c², the parts being so arranged that when the door or lid b² is thrown open it engages the plunger c' and causes the gong to ring. D is

45 a carrier adapted to receive packages such as mail matter and is provided with the hinged lid d', the carrier being adapted as stated to receive packages and when inverted to discharge the same. This carrier is provided 50 on either side thereof with a double side or flange d².

In the drawings, Fig. 1, d⁵ is the side of the

carrier and it will be understood that d² and d² are raised above this side and secured to the edges of the carrier. This flange d² is cut 55 in the manner indicated in the drawings, making ways terminating in a bearing d³. The carrier is preferably loaded at one end d⁴ for purposes which will be hereinafter described. 60

a³ is a frame set into the wall or support b' and b' and having secured thereto the lugs a⁴ and a⁴, the frame and the lugs being of a size adapted to receive the carrier and to permit the same to pass through the frame, the lugs 65 entering beneath the flanges d² and d² and through the ways terminating in the bearings d³.

I will not attempt in this specification to illustrate or describe any particular means 70 of projecting the carrier that I employ in my system but will simply refer to means for projecting the carrier for the reason that the pneumatic and other means which may be employed for this purpose are so well known 75 in the art that I deem it unnecessary to describe them in this particular. I have shown however a pipe F, connected with the tube A, which is intended to be connected with a source of air pressure, as an air pump, and 80 said pressure to the tube A is intended to be controlled by suitable valves, in the usual way, as the stop-cock f' adapted to supply pressure to the tube A, when it is desired to project the carrier D as hereinafter described. 85

The operation of my device is as follows: I first introduce into the carrier D, such mail matter or package as I desire to transmit or convey either through an aperture at d⁶ or otherwise. I then release the motive power 90 such as pneumatic pressure, or otherwise impart to the carrier a force sufficient to carry the same through the tube a'. When pneumatic pressure is employed, I of course provide the carrier with packing rings to confine 95 the air. The carrier is then directed as heretofore stated through the tube a' and as the same caroms against the shoulder of the tube a⁵ it is directed, in the line of the driving force, through the frame a³. The lugs a⁴ and a⁴ enter the ways made by the flanges d² and d² and the motion of the carrier D is arrested 100 by the lugs a⁴ and a⁴. The contents of the carrier, either by the weight of said contents,

or by the shock occasioned by the sudden arrest of the momentum of the carrier by the lugs a^4 and a^4 , causes the contents of the carrier to be discharged through the opening in 5 the top thereof, the lid a' being also thrown open by the same momentum. As heretofore stated the carrier is loaded at one end by the weight d^4 , and it will therefore be understood that as soon as the contents of the carrier are 10 discharged, and whatever weight the same may have had is removed, the carrier turns on the axis formed by the lugs a^4 and a^4 in the bearings d^3 by virtue of its load or weight d^4 , and falls by the power of gravity, through 15 the tube of guides a^2 to its point or place of departure.

In the drawings I have shown the several positions of the carrier in its progress in dotted lines.

20 Normally the door or lid b^2 is closed, but it is thrown open by the action of the carrier as the same enters the frame a^3 , and by the same force is swung upward against the plunger c' as shown in dotted lines, causing 25 the gong C to give an alarm indicating the arrival of the carrier.

What I claim is—

1. In a parcel delivery system a hollow carrier loaded at its base, and adapted to receive 30 a parcel, and when inverted to discharge the same, and provided with axis bearings near its base, in combination with means to project and guide the carrier, and to receive the same in its axis bearings, and after the carrier is inverted by the weight of its contents 35 and released by the weight of its base, to permit its return to the point of departure by the force of gravity and suitable guides, substantially as described.
2. In a parcel delivery system the combination 40 of a hollow carrier loaded at its base, and adapted to receive a parcel, and when inverted to discharge the same, ways secured to each side of the carrier, terminating in bearings, forming an axis for the carrier near its base, means to project and guide the carrier 45 and to receive the same in its axis bearings, and when the contents of the carrier are discharged to permit its return to the point of 50 departure by the force of gravity and suitable guides, substantially as described.

3. In a parcel delivery system the combination of a hollow carrier loaded at its base, and adapted to receive a parcel, and when inverted to discharge the same, ways secured 55 to each side of the carrier, terminating in bearings, forming an axis for the carrier near its base, and means controlling pneumatic pressure to project the carrier and means to guide the same, and means to receive the carrier in 60 its axis bearings, and after the carrier is inverted by the weight of its contents and released by the weight of its base, to guide the carrier to its point of departure by the force of gravity, substantially as described. 65

4. In a parcel delivery system a hollow carrier loaded at its base and adapted to receive a parcel, and when inverted to discharge the same, ways secured to each side of the carrier terminating in bearings, forming an axis for 70 the carrier near its base and means controlling pneumatic pressure to project the carrier and means to guide the same, and means to receive the carrier in its axis bearings, a pouch to receive the contents of the carrier, 75 and after the carrier is inverted by the weight of its contents and released by the weight of its base, means to guide the carrier to its point of departure by the force of gravity, substantially as described. 80

5. In a parcel delivery system the combination of a hollow carrier loaded at its base and adapted to receive a parcel, and when inverted to discharge the same, ways secured 85 to each side of the carrier, terminating in bearings forming an axis for the carrier near its base and means controlling pneumatic pressure to project the carrier and means to guide the same, and means to receive the carrier in its axis bearings, a pouch to receive the contents of the carrier and an alarm operated by 90 the movement of the carrier and means to guide the carrier to its point of departure by the force of gravity when the same is inverted by the weight of its contents and released by 95 the weight of its base, substantially as described.

KATHARINE JULIA CLINTON CARVILLE.
